ARM PROTECTOR OR THE LIKE

Irving Weisberger, New York, N. Y., assignor to
Durma-Gard, Inc., New York, N. Y.

Application May 22, 1942, Serial No. 444,028

1 Claim. (Cl. 2—59)

The present invention relates to an improved arm protector or guard and it relates more particularly to an improved type of arm guard which may be used by industrial workers or the like.

In many industries, workers therein contract many skin afflictions which result in losses to both the individual worker and industry. For example, many individuals are susceptible to the action in cutting lubricants and cooling liquids used in connection with the cutting of metal, and thus readily contract dermititis or folliculitis.

Heretofore, a two (2%) per cent solution of carbolic acid or other disinfectants and antisepsics have been added to the lubricants to prevent such undesirable condition, and in other instances the oil solvents have been heated to a high degree of temperature, all of which have proven to be unsatisfactory.

Further, minute metallic particles suspended in the cutting lubricant may prove injurious to the skin, especially if the operator uses a cloth or rag to tape the arm when coated with a film of the fluid. Injury to the arms allowed germs to enter the body and caused septic infection.

It is, therefore, the main object of my invention to provide a device which will protect the arms of a wearer from injury due to foreign particles or detrimental materials and fluids.

Another object of my invention is to provide an arm protector which is of durable and simple construction and which will completely protect the arm of the wearer from an injurious substance with which he may be working.

Still another object of my invention is to provide an arm protector of simple and durable construction, which arm protector has a wrist engaging portion which is adjustable to the wrist of the wearer and which arm protector has further means to effectively seal the upper portion thereof and prevent the same from slipping.

Other objects of my invention will be set forth in the following description and drawing which illustrate a preferred embodiment thereof, it being understood that the above statement of the objects of my invention is intended generally to explain the same without limiting it in any manner.

Fig. 1 is a front elevational view of my improved arm guard.

Fig. 2 is a sectional detail view of the elastic upper portion of the arm guard.

Fig. 3 is a sectional view along line 3—3 of Fig. 1.

Fig. 4 is a sectional view along line 4—4 of Fig. 1.

Fig. 5 is an enlarged fragmentary sectional view along line 5—5 of Fig. 2.

Referring to the drawing, 6 designates the body member of my improved arm guard, said body member having a wrist engaging portion 7 formed at one end thereof and an arm engaging portion at the other end thereof. The body member 6 may be made of rubber, rubberized fabric, plastic treated fabric, duck, oilskin or any other suitable material which fills the requirements dictated by the use to which the guard will be put. The body member 6 is formed of a single piece of fabric having its longitudinal edges sewn together by a line of stitches 2, thus forming a tubular member, the free longitudinal edges being positioned within the tubular body.

The wrist engaging portion 7 of the arm guard is formed by merely inwardly hemming the body portion 6. It is important that the wrist engaging portion be adjustable to snugly engage the wrist of the individual wearer of the arm guard and although there are many methods of accomplishing this, I found the means illustrated in Figs. 1 and 4 to be the simplest and most expedient. Along the lower edge of the wrist engaging portion 7 there is provided a series of snap fasteners 9, one of said snap fasteners being female and the other males. The wrist portion 7 may be caused to snugly engage the wrist of the wearer after the arm guard has been donned by mating any of the male snap fasteners 9 with the female snap fastener. While I have shown a single female fastener and a plurality of male fasteners, it is obvious that a single male and a plurality of female snap fasteners may be provided instead.

The upper portion 8 of the arm guard is peripherally stretchable so as to freely allow arm movement, which results in varying of the circumference of the arm in the proximity of the upper arm portion 8. In providing this stretchable portion, it is also necessary that there be avoided the biting of portion 8 into the arm thus impeding the circulation of the blood. In order to accomplish the aforesaid, I have devised the construction illustrated in the drawing.

The upper edge of the tubular body member 6 is inwardly folded to form the substantially wide hem 10, said hem 10 having positioned along its inner face the felt strip 11. The hem 10 and the abutting felt strip 11 are gathered or Shirred and are maintained in such condition by the series of elastic strips or bands 12, said strips or

bands 12 being secured to the upper portion 8 by means of the parallel lines of stitches 13, said lines of stitches 13 joining the elastic band 12, the hem portion 10 and felt strip 11. The elastic band 12 normally maintains the upper portion 8 in contracted condition. The elasticity of the upper portion 8 serves a two fold purpose, that of preventing the arm guard from slipping and that of forming an efficient seal between the arm guard and the arm of the wearer. It is obvious that any other suitable material may be substituted for the felt strip 11.

I have described my invention in a certain order, but I wish it to be understood that this does not illustrate the most efficient method of manufacturing the same. It is obvious that it would be much more expedient to form the lower hem and upper arm engaging portion and thereafter stitching together the longitudinal edges of the body member, thus forming the resulting tubular arm guard.

I have shown a preferred embodiment of my invention, but it is apparent that numerous

changes and omissions may be made without departing from its spirit.

I claim:

An arm protector for use by a wearer, said protector comprising: a continuous cylindrical body formed of a sheet of material having the longitudinal edges thereof joined by a seam extending the entire length of said body; said body having an annular wrist engaging open end with a first free edge and an arm engaging open end with a second free edge; said wrist engaging open end having secured thereto adjacent said first free edge, a first fastener element and a plurality of second complementary fastener elements any one of which is detachably engageable with said first fastener element; a substantially annular band of felt-like material secured to the inner surface of said arm end; and resilient means to constrict the arm end and compress said band between said end and the arm of the wearer, said means including a plurality of elastic strips secured to said arm end on the outer surface thereof.

IRVING WEISBERGER.
